FLEXIBLE TOWEL HOLDER OR THE LIKE

James B. Swett, Barrington, R.I., assignor to Rexall Drug and Chemical Company, Los Angeles, Calif., a corporation of Delaware

Filed Oct. 16, 1961, Ser. No. 67,115

Term of patent 14 years

(Cl. D4—3)

FIG. 1 is a perspective view of a flexible towel holder shown in operating position showing my new design;

FIG. 2 is a bottom plan view thereof shown in open flat position;

FIG. 3 is a side elevation view thereof;

FIG. 4 is a top plan view thereof; and

FIG. 5 is a side elevation view thereof shown in operating position.

The broken lines shown in FIG. 1 are for illustrative purposes only.

I claim:

The ornamental design for a flexible towel holder or the like, as shown and described.
